UNITED STATES PATENT OFFICE.

LEO D. JONES AND ARTHUR U. AYRES, OF PHILADELPHIA, PENNSYLVANIA, ASSIGNEES TO THE SHARPLES SPECIALTY COMPANY, OF PHILADELPHIA, PENNSYLVANIA, A CORPORATION OF DELAWARE.

CENTRIFUGE BOWL.

Application filed March 26, 1926. Serial No. 97,855.

Our invention relates particularly to centrifuge bowls of the tubular type having a separating chamber with an imperforate peripheral wall and of considerably greater length than diameter and a balancing chamber adjacent to one end thereof, and the leading object of our invention is to afford ready access to the balancing chamber without disturbing the adjustment of the supporting head in the shell or the balance of the bowl assembly. Further objects of our invention are to prevent leakage through the top joints of the bowl; to provide readily adjustable means by which the efflux from the bowl may be controlled, and to simplify the construction and assembly of the parts by which the bowl is supported and the flow therefrom controlled.

Bowls made in accordance with our invention have their supporting heads and shells permanently attached together, and the assembly is then given a proper running balance, and the relationship so established need not be deranged for cleaning the walls of the balancing chamber.

The balancing chamber is preferably formed by slots or sectors cut from the supporting head and covered by a detachable balanced cap extending from the periphery inwardly to a ring dam controlling the discharge of heavier liquid. The balancing chamber is separated from the separating chamber by a diaphragm preferably detachable therefrom and having an outer edge approaching and but slightly spaced from the inner wall of the shell; the diaphragm containing an axial opening or circular weir for the discharge of the lighter liquid from the separating chamber to appropriate discharge passages.

The diameters of the edges or weirs of the dams controlling the discharges of the separated constituents are suitably proportioned to secure the desired separation and separate discharge of such constituents; and the provision of the balancing chamber and of the disk or diaphragm extending across a large portion of the diameter of the bowl permits the more effective use of the bulk of the separating chamber and minimizes danger of the discharge of a constituent through the wrong discharge passages.

The separating disk or diaphragm is preferably seated in a recess in the hub of the

supporting head, and the axial opening in such disk or diaphragm communicates with passages having their upper sections formed by boring and turning the hub stem and telescoping a sleeve thereon.

The characteristic features of our improvements will more fully appear from the following description and the accompanying drawing illustrating a preferred embodiment of our invention, but it will be understood that changes may be made in details without departing from our invention as defined in the appended claims.

In the drawings, Fig. 1 is a vertical sectional view of a centrifugal machine embodying our improvements; Fig. 2 is an enlarged longitudinal sectional view of the top of the bowl; Fig. 3 is a transverse sectional view on the line 3-3 of Fig. 2; and Fig. 4 is a transverse sectional view on the line 4-4 of Fig. 2.

As illustrated in the drawings, a frame 1 has an overhanging arm 2 containing a bearing providing a support for a pulley 3, driven by a belt 4, the pulley having suspended therefrom a flexible spindle 5, for supporting and rotating the bowl 6 having a removable bottom through which it is supplied from a tube 7 with substances to be separated.

The centrifugal bowl shell 8, which is long in proportion to its diameter and has an imperforate wall thickened at the top, contains the internal threads 9 adjacent to its upper end and a shoulder or rib 10 below the termination of the threads.

The bowl head is formed from a hub 11 having a radial base from which segments are removed to form a balancing chamber comprising passages 12 spacing the radiating arms 13, which have threaded edges 95 engaging the shell threads 9 to draw the bottom of the arms against the shoulder 10. The passages 12 preferably extend from the hub to the inner surface of the bowl so as to minimize obstruction due to lodgment of heavy dirt on the outer wall and of floating dirt on the inner wall and to afford maximum access. When the head and shell have been assembled, they are fixed permanently together and the bowl is then given proper running balance by grinding, the deposition of metal or the like.

A light, balanced cap 33, containing a

channel 14 fitting over the top edge of the shell, has a threaded flange 15 screwed into the shell threads 9; a gasket 16 being interposed between the shell and the cap. A flange 17 on the cap forms a seat for a ring dam 18 having an annular bead or fin 19 drawn against the gasket 20 on the flange 17 by a clamp ring 21. The ring dam has a narrow annular edge 22 for controlling the efflux of the heavier constituent from the bowl.

The bowl head has formed therein a recess 23 in which is screwed the threaded flange of a detachable disk or diaphragm 24 having its outer edge 25 spaced but slightly from the inner wall of the shell. The inner narrow edge 26 of the disk 24 forms a weir controlling ingress of liquid to the recess 23 which communicates with longitudinal passages 27 in the hub. These passages 27 are formed by boring the hub and then turning down the stem thereof so as to bisect the passages. A tube 28 is then sleeved tightly on the stem to provide an outer wall for the passages concentric with the axis of revolution and over which the discharging liquid flows with but small depth of crest. The upper end of the stem is threaded for engagement of the coupling 29 to attach the bowl to the spindle 5.

It will be understood that, in operation, the heavier constituents of the mixture fed to the bowl are discharged from the separating chamber between the edge 25 and the inner wall of the bowl into the balancing chamber 12 and discharged therefrom over the edge 22 into the detachable receptacle 30. The lighter constituents are discharged through the axial opening in the disk 24, 40 through the recess 23 and passages 27 to the detachable receptacle 31. When it is desired to clean the balancing chamber, the cap 33 may be detached and the walls of the passages 12 thoroughly cleaned without disturbing the relationship of the supporting head and the shell and without necessity for removing the bottom of the bowl. If, however, the bottom is removed for cleaning the separating chamber, the disk 23, may, if desired, be removed to permit access to the balancing chamber from the bottom of the bowl. It will be seen that each end of the balancing chamber is partly covered by a detachable closure which when in place controls the passage of liquid thereto and therefrom and which when removed affords free access to the balancing chamber.

Having described our invention, we claim:

1. A centrifuge bowl comprising a tubular shell and a supporting head and containing a separating chamber and a balancing chamber, and a detachable closure partly covering the outer end of said balancing chamber and detachable to expose the maximum area of said balancing chamber. 65

2. A centrifuge bowl comprising a tubular shell and a supporting head and containing a separating chamber and a balancing chamber, and a detachable closure at each end of said balancing chamber and detachable to expose the maximum area of said balancing chamber. 70

3. A centrifuge bowl comprising a shell, a head comprising a hub having radiating members forming passages, and a detachable cap having a detachable annular edge controlling efflux from said passages. 75

4. A centrifuge bowl comprising a shell, an inner top member containing passages forming a balancing chamber, an outer top member secured to said shell and having means for controlling efflux from said balancing chamber, said inner top member having a stem projecting through said outer top member. 80

5. A centrifuge bowl comprising a shell, a top comprising a hub having radiating arms engaging said shell and forming passages, a cap extending partly over said passages, and a detachable ring dam controlling efflux from said passages. 90

6. A centrifuge bowl comprising a shell, a top comprising an apertured base engaging the shell and a stem projecting therefrom, said stem having longitudinal grooves in the periphery thereof, a collar fixed on the periphery of said stem and forming with said grooves discharge passages from said bowl, and a ring dam surrounding said collar and controlling the discharge of liquid from said bowl. 100

7. A centrifuge bowl comprising a shell having a ridge therein, an apertured head threaded to said shell and abutting against said ridge, a recess in said head, a ring seated in said recess and forming an annular dam, a stem concentric with said dam and having apertures therein communicating with said recess and means comprising a cap and a detachable ring connected therewith for controlling efflux from the passages in said head. 105

In testimony whereof we have hereunto set our names this 19 day of March, 1926.

LEO D. JONES.
ARTHUR U. AYRES.
